UNITED STATES PATENT OFFICE.

THOMAS F. HATHAWAY, OF ELGIN, ILLINOIS, ASSIGNOR TO ELGIN AMERICAN MANUFACTURING COMPANY, OF ELGIN, ILLINOIS, A CORPORATION OF ILLINOIS.

DESIGN FOR A MATCH, CIGAR, OR CIGARETTE CASE.

46,947.

Specification for Design.

Patented Feb. 16, 1915.

Application filed December 5, 1914. Serial No. 875,732. Term of patent 3½ years.

To all whom it may concern:

Be it known that I, THOMAS F. HATHAWAY, a citizen of the United States, residing at Elgin, in the county of Kane and State of Illinois, have invented a new, original, and ornamental Design for Match, Cigar, or Cigarette Cases, of which the following is a specification, reference being had to the accompanying drawing, forming a part thereof.

In the drawing, the figure is a plan view of a match, cigar or cigarette case, showing the design of the present invention.

I claim:

The ornamental design for a match, cigar or cigarette case substantially as shown.

THOMAS F. HATHAWAY.

Witnesses:

PHILIP E. C. HOUY,
F. C. ANABUSCH.
